UNITED STATES PATENT OFFICE.

OTIS DUNCAN, OF BIRMINGHAM, ALABAMA, ASSIGNOR OF ONE-THIRD TO DAVE GOLDSTEIN, OF BIRMINGHAM, ALABAMA.

TRACK GAUGE AND BRIDLE BAR.

Application filed April 13, 1923. Serial No. 631,947.

To all whom it may concern:

Be it known that I, OTIS DUNCAN, a citizen of the United States of America, residing at Birmingham, in the county of Jefferson, State of Alabama, have invented certain new and useful Improvements in Track Gauges and Bridle Bars, of which the following is a specification.

My invention relates to a combination gauge and bridle bar for railway tracks which is adapted to be applied permanently to the roadbed but which can be adjusted as required and removed when desired without disturbing the tracks.

It is well understood by those skilled in the art that timber cross ties are capable of sustaining the tracks on grade or surface level long after they would not hold the spikes so as to prevent the tendency of the rails to spread. As a result, the railroads in order to maintain the maximum life from their cross ties are resorting more and more to the practice of producing bridle bars, particularly on curves and in yards where the tracks are subjected to most severe usage. The most serviceable bridle bar heretofore used has been the one formed as an integral body which thus automatically preserves the gauge and holds the tracks against spreading, but when it is required to be removed or changed it is necessary to tear up the tracks and it is incapable of adjustment for change in gauge.

The purpose of my invention is to provide a bridle bar which is intended to be applied to the tracks as a permanent safety appliance but which can be readily removed when desired without disturbing the track and which is capable of both indicating the gauge of the track and of being adjusted to provide a variation in the gauge which is important on curves. It is a special object of my invention to make the device so simple and rugged in its construction that the expense will be low, the labor incident to applying or removing it will be negligible, and the method of use and gauge adjustment are so obvious that the most unskilled track employee can still operate it successfully, this making it practically available to the railroads for the purpose of obtaining maximum life from their cross ties.

A further object is to provide an improved wedge for adjustably connecting the bar sections which shall have a safety shoul-

der to limit adjustment to the maximum gauge of 4' 9" and which shall present a straight edge to the bifurcated end of one bar section.

As illustrative of the preferred embodiment of my invention, reference is made to the accompanying drawings, in which:—

Fig. 1 illustrates a track in vertical transverse cross-section and shows my improved track gauge and bridle bar in side elevation.

Fig. 2 is an enlarged perspective view showing the assembled bridle bar detached from the track.

Fig. 3 is an enlarged detail plan view of a wedge showing the preferred arrangement of cotter key holes therein for adjusting it to the different gauges.

Fig. 4 is an enlarged side view of one of the bridle bar sections marked with the gauge scale for the track.

Fig. 5 is an enlarged view in cross-section taken on the line 5—5 of Fig. 2, showing the interlocked ends of the bridle bar sections with my preferred type of wedge in operating position.

Similar reference numerals refer to similar parts throughout the drawings.

According to the embodiment of my invention illustrated, I show a railway track formed by rails 1 and 2 which are attached by spikes 3 to the cross ties 4 which are set on the roadbed 5. The bridle bar is made up of two sections 6 and 7, each section having at its outer end a hook 8 adapted to engage the outer base flange of a rail while the horizontal body portion of the bar passes under, preferably in contact with, the bottom of the rail. The bridle bar section 6 near its inner end is given a right angled twist to form the interlocking end 9 which stands vertical and is shown more clearly in Fig. 4, where it will be seen that it is provided with an elongated horizontal slot 10 and between said slot and the twist with notches or indentations 11 forming a track gauge scale which are marked to indicate quarter inch variations in the track gauge from 4' 8" to 4' 9". The bridle member 7 at its inner end is bifurcated and adjacent to its bifurcated portion is twisted 90°. The bifurcated end is adapted to receive between the spaced elements 12 thereof the interlocking end 9 of the bar 6. The furcations are also provided with aligning slots 13, corresponding to the slot

10, and adapted to register therewith when the bars are assembled as shown in Fig. 2. A wedge is adapted to be driven through the registering slots 10 and 13 to interlock 5 the bar members in the relative adjustment to hold the desired track gauge which is indicated by the relation of the inner end of the bar 7 to the gauge scale 11. The wedge may be of the symmetrical tapered form 14 10 shown in Fig. 3, wherein a symmetrical tapering plate is provided on each side with a staggered series of holes 15 which are adapted to receive cotter keys 16 to lock the wedge in adjusted position. The holes are 15 arranged on quarter inch spaces so that the bar can be adjusted relatively to the gauge scale.

In Fig. 5 I show the preferred type of wedge 17 which has a straight edge 18 20 adapted to engage the end walls of the slots 13 in the bifurcated end of the bar 7 while presenting a tapered edge to the opposite end of the slot 10 in the interlocking end 9 of the bar 6. The advantage of using a 25 straight edge against the bifurcated end of the member 7 is to prevent a tendency of the latter, when engaging a bevel or taper edge, to cock the wedge which might shear the cotter key, or vary the length of the 30 bridle bar so as to change the gauge. It will be noted that this preferred type of wedge is provided at the end of its straight edge with an offset shoulder 19 in line with the holes 16 for the maximum gauge. This 35 will prevent the wedge being adjusted beyond the 4' 9" gauge or slipping out should one or more of the cotter keys fail.

In operation, the bar members 6 and 7 are 40 hooked on the outside edges of the rail bases with the inner end of the bar 6 loosely fitted in the bifurcated end of the bar 7. The wedge is then inserted and as it is 45 driven in it acts to draw the bar members together, reducing the gauge as the wedge is driven in. By reference to the gauge scale the exact gauge of the track can be at all times determined, and when the desired 50 gauge has been obtained the two cotter keys are inserted so as to prevent the withdrawal of the wedge. From time to time, if desired, the cotter keys can be removed and the wedge adjusted to change the

gauge, so as to increase or decrease it as conditions may require.

The shoulder at the small end of the 55 straight side wedge 17 will engage the bar when adjusted to the maximum gauge, thereby preventing accidental disengagement of the wedge or careless work which might otherwise permit a gauge in excess 60 of 4' 9".

Though I have described with great particularity the details of the embodiment of the invention herein shown, it is not to be construed that I am limited thereto, as 65 changes in arrangement and substitution of equivalents may be made by those skilled in the art without departing from the invention as defined in the appended claims.

Having thus described my invention, 70 what I claim as new and desire to secure by Letters Patent, is:—

1. A bridle bar and gauge formed by two bars, each having at one end a rail engaging hook and at the other end a slotted portion, one of said slotted portions being bifurcated and adapted to receive the other, and a wedge inserted through the registering slots in said bar ends to hold the assembled bar in place with the desired gauge 75 adjustment, said wedge having one straight side disposed to operatively engage the bifurcated end portion of one bar and having a shoulder disposed to interlock with the bridle bar when it has been adjusted to the 80 maximum permissible track gauge.

2. A bridle bar and gauge comprising two members, each having a rail engaging hook at one end and having the other end 90 twisted to stand in vertical position and provided with a slot, a wedge adapted to be inserted through said slots to adjustably interlock said members, said wedge having a shoulder adapted by engagement with the bridle bar to stop it in position of maximum track gauge adjustment, and removable cotter keys to hold the wedge in adjusted position.

In testimony whereof I affix my signature.

OTIS DUNCAN.
